ARTIFICIAL FISHING WORM

Bill K. Norman, P.O. Box 6383, South Station,
Fort Smith, Ark. 72901

Filed May 15, 1972, Ser. No. 253,691

Term of patent 14 years

Int. Cl. D22—05

U.S. Cl. D22—27

FIG. 1 is a side elevation view of the artificial fishing worm incorporating the design of the present invention.

FIG. 2 is a top plan view of the artificial fishing worm illustrated in FIG. 1.

FIG. 3 is a top plan view of the artificial fishing worm in an alternate position as compared to the artificial fishing worm illustrated in FIG. 2.

FIG. 4 is a rear view of the artificial fishing worm looking from the end of the artificial fishing worm's tail forward toward the artificial fishing worm's head.

FIG. 5 is a cross-sectional view taken on the line 5—5 in FIG. 1.

FIG. 6 is a cross-sectional view taken on the line 6—6 in FIG. 1.

I claim:

The ornamental design for an artificial fishing worm, substantially as shown and described.
